UNITED STATES PATENT OFFICE.

HENRY MESINGER, OF NEW YORK, N. Y.

SEAT SUPPORT.

Application filed April 17, 1925. Serial No. 23,758.

To all whom it may concern:

Be it known that I, HENRY MESINGER, a citizen of the United States, and a resident of the city of New York, county and State of New York, have invented certain new and useful Improvements in Seat Supports, of which the following is a specification.

This invention relates to seat supports and more particularly to a novel means for 10 yieldably supporting and cushioning a seat such as is provided for bicycles, motorcycles and other vehicles.

It is a more particular object of the invention to provide auxiliary cushioning 15 means interposed between the vertical spring post for the saddle or seat and the under side of said seat and connected with the latter whereby abnormal shocks or jars will be effectively absorbed.

20 In one practical embodiment of my present improvements, I provide a laminated leaf spring structure extending longitudinally beneath the seat and connected at its forward end with the vehicle frame, said leaf 25 spring at its rear end having sliding engagement with anti-friction bearing means fixed to the rear end of the seat and intermediate of its ends having sliding connection with the upper end of the spring post 30 for the seat.

It is another object of my invention to provide means whereby certain of the leaves or laminations of the cushioning spring may be longitudinally adjusted relative to the 35 others and with respect to the point of connection of said spring with the upper end of the seat post.

With the above and other objects in view, the invention consists in the improved seat 40 support and in the form construction and relative arrangement of the several parts thereof as will be hereinafter more fully described, illustrated in the accompanying drawing, and subsequently incorporated in 45 the subjoined claims.

In the drawing, wherein I have illustrated one simple and satisfactory embodiment of the invention, and in which similar reference characters designate corresponding 50 parts throughout the several views,—

Figure 1 is a side elevation illustrating my invention as applied to a saddle seat such as is used on bicycles or motorcycles, certain 55 of the parts being shown in section;

Fig. 2 is a bottom plan view;

Fig. 3 is a detail transverse section taken on the line 3—3 of Fig. 1;

Fig. 4 is a similar section taken on the line 4—4 of Fig. 1;

Fig. 5 is a transverse section taken on the line 5—5 of Fig. 1;

Fig. 6 is a fragmentary bottom plan view illustrating a slightly modified form of the device;

Fig. 7 is a rear end elevation of the seat; 65

Fig. 8 is a longitudinal section taken on the line 8—8 of Fig. 7, and

Fig. 9 is a similar section taken on the line 9—9 of Fig. 7.

Referring in detail to the drawing, 5 70 designates a portion of the vehicle frame in which the vertically movable spring post 6 for the support of the seat or saddle is mounted in the usual manner. The saddle seat 8 may be of any approved construction 75 and is provided at its rear end with the usual cantle plate 9. The customary wire spring 10 is also arranged beneath the seat for the purpose of longitudinally tensioning the latter and as herein shown is provided 80 with a transverse intermediate portion 11 seated under a curved lip 12 on the forward edge of the cantle plate 9. At opposite ends of said intermediate portion 11, this wire spring is fixed to the cantle plate by 85 suitable bolts 13. The spaced side portions of the spring 10 are forwardly extended from the cantle plate beneath the seat 8, in convergent relation to each other and are suitably connected with a plate 14 fixed to 90 the under side of the front end or pommel of the seat, as for instance by means of a suitable bolt indicated at 15.

To the opposite sides of the longitudinal bar of the frame 5 the upwardly projecting 95 plates 16 are rigidly fixed by the transverse bolt 17 and between the upper ends of these plates the forward end of a longitudinally disposed channel shaped bar 18 is pivotally mounted upon the transverse bolt 19. The 100 rear end of this bar is connected with the forward end of the saddle seat by the bolt 15 as clearly shown in Fig. 1 of the drawings.

Upon the upper end of the spring post 6 a horizontally disposed plate 20 having side flanges 21 is rigidly fixed. These flanges adjacent their opposite ends are notched or recessed to receive the ends of the spaced bearing rollers 22. The rollers are retained 105 in said seats by the side walls of a vertical 110

U-shaped housing 23, said side walls being fixed to the flanges 21 by the screws 24. The top wall of this housing adjacent its forward end is formed with a pocket or seat 25 for an upper bearing roller 26 positioned in the vertical plane of the forward lower bearing roller 22.

Supplementing the sustaining action of the spring post 6 for the purpose of absorbing abnormal shocks or jars, I provide a laminated spring structure which includes an upper spring leaf 27, the forward end of which is bent to provide a sleeve thereon through which the transverse bolt 19 extends, 15 said sleeve being disposed within the channel of the bar 18. The second leaf 28 of this auxiliary cushioning spring has its forward end 28' downwardly extended and engaged against the under side of the sleeve 20 on the forward end of the spring leaf 27 as shown in Fig. 1 of the drawings. Beneath the leaf 28 the additional spring leaves 30 and 31 respectively are arranged, said lower leaf 31 being connected at its rear 25 end with a bolt 32 which connects the ends of a U-shaped clip member 33 embracing the several leaves or laminations of the spring structure at a point rearwardly of the bearing housing 23. It will be noted 30 that the several leaves or laminations of the spring successively decrease in length from the upper to the lower lamination, and therefore offer successively increasing resistance to vertically applied pressure. For 35 the purpose of regulating this resistance, I provide the two lower leaves 30 and 31 adjacent their forward ends with suitable notches or recesses 34 for the purpose of receiving the bolts 35 connecting the ends 40 of two transverse plates 36 extending above and below the series of spring leaves. The two upper spring leaves 27 and 28 are provided with a plurality of such notches or recesses 37 in their opposite edges spaced longitudinally from each other. Thus, it 45 will be apparent that by shifting the two lower leaves 30 and 31 of the spring longitudinally with respect to the two upper leaves and engaging the bolts 35 in selected 50 recesses or notches 37 of the latter leaves, the rear end portions of the lower leaves 30 and 31 may be adjustably positioned with relation to the bearing rollers 22 and 26 mounted on the upper end of the spring post 6 to thereby increase or decrease the 55 resistance offered by the rear end portion of the laminated spring structure to vertically applied pressure.

To the under side of the cantle plate 9 a 60 plate 38 is fixed at its rear end, the forward end of said plate having a transverse seat 39 formed therein for a bearing roller 40. This plate and bearing roller are enclosed within a suitable housing 41 fixed at its 65 rear end to the cantle plate and open at its

forward end. As clearly shown in Fig. 1 of the drawings, the rear end of the upper leaf 27 of the laminated spring structure extends longitudinally into this housing between the bearing roller 40 and the bottom 70 wall of the housing and exerts an upward bearing pressure against the under side of said roller.

In the operation of the device above described, it will be apparent that the weight 75 of the rider on the seat 8 is normally sustained by the spring post 6, there being little flexure of the longitudinally extending laminated spring structure from its normal condition. When, however, the wheels of the 80 vehicle encounter obstructions or ruts in the road surface, resulting in an abnormal shock or jar to the vehicle frame, such shock will be cushioned by the longitudinally extending auxiliary leaf spring, said spring at 85 its forward end turning about the bolt 19 and flexing at its rear end as the bearing roller 40 moves downwardly on the upwardly curved end of the spring lamination 27. In this abnormal vertical movement of the 90 seat relative to the vehicle frame, the intermediate portion of the laminated spring will shift longitudinally relative to the upper end of the spring post 6 between the bearing rollers 22 and 26. Thus, it will 95 be apparent that in this manner such shocks or jars will not be transmitted to the body of the rider but will be effectively absorbed by the longitudinally extending laminated spring interposed between the seat and the 100 supporting post 6 therefor. By adjusting the lower spring leaves in the manner above explained, the responsiveness of the laminated spring structure may be properly regulated in accordance with the weight of 105 the rider.

In Figs. 6 to 9 inclusive, I have illustrated an alternative means for yieldably connecting the rear end of the longitudinally extending spring with the seat. In this construction I provide a transversely positioned multi-ply leaf spring indicated at 42, the central leaf of which is extended beyond the ends of the upper and lower leaves and pivotally connected by the shackles 43 with the depending members 44 which are pivotally suspended from the transverse pins or bolts 45 in the rear ends of plates 46 which clamp the wire spring 10' to the under side of the cantle plate 9.

The transversely disposed leaf spring 42 at its center extends over and upon the rear end of the uppermost leaf of the longitudinally positioned spring which is mounted upon the seat post in the manner above described, and is rigidly fixed thereto by means of the bolt 47. It will be apparent from this construction that the transverse spring 42 connecting the rear end of the longitudinal spring with the seat provides 125 130

additional or supplemental shock absorbing means and also relieves the rearwardly extending part of the longitudinal spring of excessive strains. By connecting the ends 5 of this transverse spring by means of the shackles with the pivoted members 44, the desired flexibility in the connection between said spring and the rear end of the saddle seat is obtained. In many cases, this last 10 described construction may be found preferable to that illustrated in Fig. 1 of the drawings.

From the foregoing description considered in connection with the accompanying drawing, 15 the construction, manner of operation and several advantages of my present improvements will be clearly understood. It will be seen that I have devised a yieldable support for vehicle seats, which is relatively 20 simple in its construction as well as effective and reliable in operation. I have herein referred to the device as primarily designed for use in connection with such saddle seats as are employed upon bicycle and motorcycles, 25 but it will of course, be manifest that the essential features of my invention might also be incorporated in a similar supporting means for various other kinds of seats used for other purposes. It is, therefore, 30 to be understood that while I have herein shown and described several simple and practical embodiments of the device, the same is nevertheless susceptible of considerable modification in the form, construction 35 and relative arrangement of its several parts, and I therefore, reserve the privilege of adopting all such legitimate changes as may be fairly incorporated within the spirit and scope of the invention as claimed.

40 I claim:

1. In combination with a seat and supporting post therefor, a cushioning spring interposed between the seat and said post and having parts relatively adjustable with 45 respect to the post, means connecting said spring parts with the post, and means for securing the spring parts in adjusted position with respect to said post to vary the resistance of said spring to vertical movement of the seat with respect to the post.

2. In combination with a seat and supporting post therefor, a longitudinally extending multi-ply leaf spring connected with said post and yieldably sustaining the 55 seat for movement relative thereto, and means for longitudinally adjusting certain of the spring leaves relative to the post to vary the resistance of said spring to vertical movement of the seat with respect to the post.

3. In combination with a seat and supporting post therefor, cushioning means for the seat mounted upon the upper end of said post to yieldably resist vertical movement 60 of the seat relative to the post, said

cushioning means including independently adjustable elements and means connecting said elements with the post for movement relative thereto, and means for securing said cushioning elements in their adjusted positions to produce a desired resistance of the cushioning means to the vertical movement of the seat with respect to the post. 70

4. In combination with a seat and supporting post therefor, a cushioning spring 75 extending longitudinally beneath the seat pivotally held at its forward end and connected at its rear end with said seat, and means slidably connecting said spring with the upper end of said post, said means including anti-friction bearing members engaged with the upper and lower sides of said spring.

5. In combination with a seat and supporting post therefor, a cushioning spring 85 extending longitudinally beneath said seat pivotally held at its forward end, means on said seat bearing upon the rear end of said spring and movable with the seat longitudinally of said spring, and means slidably 90 connecting said spring intermediate of its ends with the upper end of said post.

6. In combination with a seat and supporting post therefor, a cushioning spring 95 extending longitudinally beneath said seat pivotally held at its forward end, means on said seat bearing upon the rear end of said spring and movable with the seat longitudinally of said spring, and means slidably connecting said spring intermediate of its 100 ends with the upper end of said post, said means including spaced anti-friction members engaged by the lower side of said spring.

7. In combination with a seat and supporting post therefor, a cushioning spring 105 extending longitudinally beneath said seat pivotally held at its forward end, means on said seat bearing upon the rear end of said spring and movable with the seat longitudinally of said spring, and means slidably connecting said spring intermediate of its ends with the upper end of said post, said means including spaced anti-friction members engaged by the lower side of said 110 spring, and an additional anti-frictional member opposed to one of the first-named members and engaged by the upper side of said spring.

8. In combination with a seat and supporting post therefor, a cushioning spring 115 extending longitudinally beneath the seat and pivotally held at its forward end, an anti-friction bearing member interposed between the rear end of the seat and the 120 rear end of said spring, and anti-friction bearing members mounted upon the upper end of said post and engaged respectively upon the upper and lower sides of said 125 spring. 130

9. In combination with a seat and supporting post therefor, a cushioning spring extending longitudinally beneath the seat and pivotally held at its forward end, anti-friction means carried by the rear end of the seat and having rolling bearing pressure upon the upper side of said spring at its rear end, a housing on the upper end of the post through which the intermediate portion of said spring extends, and anti-friction bearing members mounted in said housing and engaged with the upper and lower sides of said spring.
10. In combination with a seat and supporting post therefor, a multi-ply leaf spring extending longitudinally beneath the seat and pivotally held at its forward end, the leaves of said spring successively decreasing in length from the upper to the lower leaf, means carried by the rear end of the seat having rolling bearing pressure upon the rear end of the upper spring leaf, means connecting said leaf spring with the upper end of said post, and means for longitudinally adjusting certain of the spring leaves relative to the others and with respect to the point of connection with said post to vary the yieldable resistance of said spring to the vertical movement of the seat with respect to the post.
11. In combination with a vehicle frame, a seat and vertically movable supporting post therefor, means pivotally connecting the forward end of the seat with the vehicle frame, a cushioning spring extending longitudinally beneath the seat and secured at its forward end in fixed relation to the frame, means carried by the seat having rolling bearing pressure upon the upper side of said spring at its rear end, and means slidably connecting said spring between its ends with the upper end of said post.
12. In combination with a vehicle frame, a seat and vertically movable supporting post therefor, means pivotally connecting the forward end of the seat with the vehicle frame, a cushioning spring extending longitudinally beneath the seat and secured at its forward end in fixed relation to the frame, means carried by the seat having rolling bearing pressure upon the upper side of said spring at its rear end, means slidably connecting said spring between its ends with the upper end of said post, and means for varying the resistance of the rear end portion of the spring to vertical movement of said seat with respect to the post.

In testimony that I claim the foregoing as my invention, I have signed my name hereto.

HENRY MESINGER.
